(57) **CLAIM**

The ornamental design for a surface ornamentation for a grip for a sporting device, as shown and described.

DESCRIPTION

FIG. 1 is a right side perspective view of a surface ornamentation for a grip for a sporting device, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings depict a sporting device that forms no part of the claimed design.

1 Claim, 4 Drawing Sheets
